ration of Japan

Filed Mar. 4, 1964, Ser. No. 78,869

Claims priority, application Japan Sept. 7, 1963

Term of patent 14 years

(Cl. D48—27)

FIG. 1 is a perspective view of a gas lighter for cigarettes or the like showing my new design;

FIG. 2 is a side elevation thereof;

FIG. 3 is a top plan view thereof;

FIG. 4 is an end elevation as seen from the left of FIG. 2; and

FIG. 5 is a side elevation thereof as shown in operating condition.

The characteristic feature of my new design resides in the fuel reservoir portion of the lighter, said portion having a transparent area and an opaque area, which areas are defined by the variation in shading shown.

The underside of the lighter is the same in appearance as the side shown.

I claim:

The ornamental design of a gas lighter for cigarettes or the like, as shown and described.
